DISPLAY DEVICE

Sholom Kass, Philadelphia, Pa., assignor to Fischer & Porter Company, Hatboro, Pa., a corporation of Pennsylvania

Filed July 24, 1959, Ser. No. 829,241

6 Claims. (Cl. 40—53)

This invention relates to display devices particularly adapted for the display of numerals, letters or other matters under electrical control.

Various types of display devices are in use for exhibiting numerical or alphabetical information, and the computer and control field constitutes one of extensive present day use. Considering first this type of use, the general desire is to exhibit numbers in decimal form, and to this end there are commonly used devices of three general types. In one of these, arrays of lamps are provided illuminated in accordance with special codes to exhibit the outlines of the numerals. In another arrangement, the numerals carried by film areas are selectively projected by lamps upon a screen. In still another arrangement, numerals in the form of bent wires are superimposed to constitute selectable cathodes in gas-filled tubes. Considering the fact that in computing apparatus the computations are generally carried out in a binary system, there is, obviously, the necessity for providing a translating matrix of considerable complexity between the output from the computer and the display device in order to secure control signals for the display device corresponding to the binary (or binary-decimal) inputs. Furthermore, rather elaborate relay systems are required to provide the amplification of power necessary for illumination of the display device.

In accordance with the present invention a display device is provided which in itself provides in simple electromechanical fashion the translation of a binary type of input into a decimal or even further extended output. Furthermore, devices in accordance with the present invention require very little control power, and may be operated directly from the outputs of low power transistor circuits. (It may be here remarked that while substantial power may be involved for the bright illumination of the display device, one or more electric bulbs may be continuously illuminated directly from a power line and require for their operation no control relays or the like.)

In brief, in accordance with the invention, a pair of masks provided with selectively located openings are arranged to be moved relatively to each other to desired numbers of positions in each of which there is produced a different display. In a simple form of the invention each display device is capable of producing sixteen different characters requiring inputs through only four channels. The sixteen displays may, for example, include the ten decimal digits, a decimal point, plus and minus signs, a dollar mark, and a blank to exhibit only a space. In a more elaborate form involving six input channels there can be provided a display device capable of exhibiting thirty-six different characters which, as will be evident, suffices for the display of the entire English alphabet in addition to the ten decimal numerals, and if zero and the letter O are the same in shape, there may also be exhibited a blank.

The last consideration gives rise to the possibility of use not only in technical apparatus but for advertising, since an assembly of devices may spell out any desired message. The arrangement just mentioned does not ex-

2

haust the possibility of six input channels which theoretically would provide sixty-four characters, and a further elaboration of the mechanical aspects of the invention may give rise to a display device having wide capabilities so as to be possibly used, in advertising particularly, for the display of silhouettes or even fairly elaborate pictures.

Considered generally, display devices in accordance with the invention make the most effective use of input apparatus of any given degree of complexity. As will become obvious, perforated tapes or multi-channel magnetic tapes may be read to provide message inputs for use in advertising or the like, while in the case of numerical computer or similar apparatus the available outputs are directly applicable to the display control.

The objects of the invention have to do with the attainment of the foregoing and the general objects as well as specific ones relating to details of construction and operation will become apparent from the following description, read in conjunction with the accompanying drawings, in

20 which:

Figure 1 is a diagrammatic front elevation of the operating parts of a simple display device provided in accordance with the invention;

Figure 2 is a horizontal section with various parts broken away showing structural features of the display arrangement of Figure 1;

Figure 3 is a wiring diagram showing the electromagnetic control arrangement responsive to four input channels;

30 Figure 4 is a diagram illustrating the principles involved in layout of displays and operation;

Figure 5 is a diagram illustrating the fashion in which maximum use is made of available space as applied particularly to a display device capable of exhibiting thirty-six different characters;

Figure 6 is a diagram similar to Figure 5 but showing the possibility of utilizing other than straight line displacements of masks;

40 Figure 7 is a mechanical linkage diagram illustrating particularly an arrangement for providing a display device capable of exhibiting thirty-six different characters;

Figure 8 is a diagram indicating electrical connections suitable for transient pulse settings and for readout;

45 Before discussing the theory of operation and its general aspects, the invention may be best made clear by first referring to Figures 1 and 2 exhibiting a simple arrangement capable of providing sixteen different characters utilizing four input channels. To avoid complexity of illustration, mounting, guiding and other parts which are subject to obvious and wide choice are omitted, there being primarily illustrated only the operating elements of a single unit or device. It will, further, be understood that such devices are designed to be associated side by side to represent multiple digit numbers, words, or the like, each device providing a choice of characters to be exhibited in a particular fixed position, such as a single order of a decimal number.

55 Indicated at 2 and 4 are a pair of "plates" which are arranged in close parallelism and which are to be moved to various relative positions. These plates may be of thin sheet metal perforated as hereafter indicated or may be in the form of photographic film or plates provided with light-transmitting openings which may be formed, as will later be obvious, by a photographic exposure and development process.

60 The plates 2 and 4 are guided for their relative movements in close parallel proximity by means not shown in detail but which may take the form of suitable guide slots provided in a housing 6 which is indicated in Figure 2 and which is provided with a display opening covered by a glass or plastic window indicated at 7.

The plate 2 is provided along two of its edges with slots 8 and 10, shown as arranged at right angles with each other, in which are received the elongated ends of electro-magnet armatures 12 and 14. As indicated, the slots 8 and 10 are longer than the portions of the armatures received therein, so that as one armature moves the plate 2 may slide on the other armature to be located in a definite position with the movement of the plate 2 being parallel to itself without rotation. Similarly, the plate 4 is provided with slots 16 and 18 also embracing transversely elongated extensions at the ends of electromagnet armatures 20 and 22. The various armatures referred to form parts of electromagnet assemblies of windings and cores indicated at 24, 26, 28 and 30. Each of the electromagnet assemblies may be of the form conventionally used for relays, though in the present instance there is no necessity for the provision of relay contacts. The several windings are energized as indicated in Figure 3 from separate binary input channels 32, 34, 36 and 38 which may be considered, by way of example, to correspond to binary inputs of the orders 0, 1, 2 and 3 as indicated at the right of Figure 3. The armatures may be formed of spring material or may be separately spring mounted and when the electromagnets are deenergized rest against stops indicated at 40 which, if desired, may be adjustable to secure accurate alignment of the plates. When the electromagnets are energized their armatures are brought to definite positions, and it will be evident, therefore, that each of the plates 2 and 4 occupies at any time for any individual component of motion either one or the other of two fixed positions.

Illumination is to be provided by transmission through aligned openings in the plates 2 and 4, and for this purpose the illuminating arrangement illustrated in Figure 2 may be used in small units. Behind the plates there is a block of plastic such as Lucite capable of freely transmitting light, which has bevelled sides 42 desirably frosted and backed up with reflecting coating so as to make maximum use of the available light. In a socket 44 formed in the center of the block 42 there is located a lamp 46 which furnishes the illumination for the unit. The lower portion of the socket 44 may be frosted to prevent rays from passing directly from the filament through the openings, and it will be evident that with suitable frosting there may be secured substantially uniform illumination over the display area which is indicated at 47 in Figure 1 and which corresponds to the display opening in the housing 6. For larger units or more intense illumination several lamps may be provided in obvious fashion. In the ordinary use of the device the lamps may be continuously lighted, though, if desired they may be deenergized to provide a blank indication.

Using thin plates it is easily possible to secure readability through angles exceeding 45° off center. Still greater angles of visibility may be secured by providing a beaded window at 7 or by inserting beads in the front plate or by equivalent light spreading means.

Movements are imparted to the plates 2 and 4 as follows:

The armature 14 when energized effects a displacement of plate 2 to the right through a unit distance represented by the vector 48. The armature 12 when energized moves the plate 2 downwardly through a distance corresponding to two units as indicated by the vector 50. The armature 20, when energized, moves plate 4 to the left a distance of two units as indicated by the vector 54. The armature 22, on energization, moves the plate 4 upwardly through a unit distance as indicated by the vector 52. It may be remarked that these vectors are enlarged in scale for simplicity since in the scale of construction in Figure 1 the movements would actually be quite small, though of single unit and double unit extents as described. The result of the foregoing is, obviously, that by selective energization of

the electromagnets the plates 2 and 4 may be located in any one of sixteen relative positions. The array here is rectangular. It is only relative positions of the plates which are of significance, and with a more elaborate control system it will be evident that one of the plates might be stationary and movements might be applied only to the other. However, for maximum simplicity, and the direct utilization of the binary signals on four channels it is advantageous to use an arrangement such as described in which each plate has two freedoms of movement transverse to each other. By having the respective horizontal movements applied to the two plates of different extents, as shown and described, the relative horizontal positions are four in number. The same is true of the vertical positions. Of course, one of the plates might have only unit movements imparted to it in both directions, while the other plate might have double unit movements, applied to it in both directions.

The situation involved in exhibiting characters is illustrated in Figure 4. Initially assuming that the front plate 2 has light-transmitting areas or openings regularly disposed thereon as indicated at 56, it will now be apparent that in view of the operations described a particular opening such as that at the extreme upper left of 25 the figure will have a relative movement with respect to the rear plate to bring it into any one of the sixteen positions indicated at 58 by the small x's, one of these positions being that illustrating the opening itself. Light-transmitting openings are provided in the rear plate 4 30 to correspond selectively, in accordance with the character to be displayed, with the various positions which may be assumed by each of the openings 56. For illustrative purposes, Figure 4 shows the numeral 2 in chain lines as it would be outlined by coincident openings in the two plates when, assuming in the discussion of relative movement, the rear plate to be fixed and the front plate to have its openings in the positions illustrated at 56. The back plate would, for this condition have openings as indicated at 60 so that for this 40 relative position of the plates light would pass through the aligned openings represented as unshaded in Figure 4, the shaded openings corresponding to positions at which the rear plate would have no openings, thereby occulting the light.

45 For purposes of further illustration, there is also indicated in Figure 4 the display of the numeral 5. Assuming that this is to be displayed when a relative position corresponds to that indicated at 64 in the array 58, the back plate would be provided with openings centered 50 at the points 66 arranged along the dotted line 68 outlining the numeral 5. As will now be evident, the openings 56 should be of such diameter that in the successive relative positions they would not overlap; i.e., their diameters should be slightly less than the unit steps of movement imparted to the plates relatively to each other. Under these conditions there will be no appearance of "ghosts" of characters which are not to be displayed when the input signals are such as to display any character. While equally spaced openings 56 are illustrated as pro- 55 vided in the front plate, consideration of the style of the characters to be exhibited may indicate a more advantageous distribution of these openings to give rise to a more desirable shape of the characters. For example, considering the ten digital numerals, the only one which ex- 60 tends to the furthest lower right hand corner of the display area is the numeral 2. Consequently, there would be some freedom of choice of the position of the lower right hand opening to provide, for example, a slight upturn of the bottom stroke of the 2. Artistic considera- 65 tions of this type may be given to secure the best shaping of the numerals (or letters), the only requirement being that in the range of movement of any opening it should not infringe adversely on the required opening position of another numeral so as to give rise to an 70 illuminated spot which should be dark.

As will be clear from the foregoing, the display may be a bold one consisting of a small number of large openings relatively widely spaced and corresponding to relatively large movements of the plates; but alternatively, the openings may be quite small consistent with much smaller movements of the plates so that a character might be displayed not in a linear outline of light spots but rather as an area representation consisting of closely spaced spots approaching a "half-tone" type of representation. It is particularly in the case of the last type of representation that it is advantageous to utilize photography to provide the transparent dots in the plates, and for better utilization of area the dots may be polygonal rather than circular, for example, rectangular in the instance so far described. If the light transmitting openings are small and consequently may be more closely spaced, with correspondingly smaller increments of movements imparted to the plates, the openings in the plate which does not have a regular array of openings may be provided by photographic exposure (and photographic reversal) through the one having the regular array and the use of a suitable negative, exposures being made for every particular relative position which the plates may have. In fact, by such photographic making of the plates, a negative having variable density areas may be used to provide light transmitting openings of different densities. Thus, a considerable degree of shading of the character may be produced, approaching a rendition which may be of shaded or half-tone appearance. In this fashion, for example, one of the relative positions of the plates might well exhibit a face, scene, product, or the like.

The sixteen positions illustrated in Figure 4 at 58 exceed the number required for numerical indications, and the density of openings may be increased by using only a 3 x 4 configuration giving 12 relative positions for the integers and, for example, a dollar sign and a blank.

The density of distribution of the light-transmitting opening may be appreciably increased if the relative movements between the plates are not rectangular but are, rather, at an angle of 60° with respect to each other. This condition is illustrated in Figure 5 which, furthermore, illustrates the aspect of securing from a single display device the exhibition of 36 different characters. An opening in the regular array on one of the plates (which may be considered the front plate for simplicity of description) is indicated at 70, while the closest positions of adjacent openings are indicated at 70'. The successive positions which may be taken by the opening 70 are indicated by the stacked circles 72, the openings, of course, necessarily having a slightly smaller diameter than these circles. For the purpose of illustrating movements, the increments to be imparted by way of relative movement are indicated at 1, m and n, m being twice 1 and n being three times 1. Assuming, for aspects of simplicity of operation as discussed later, that increments of 1 plus m are not used, the successive positions horizontally by way of displacement from position 70 would be 0, 1, m, n, 1+n and m+n. This, considering the two sets of displacements gives rise to thirty-six relative positions, sufficing for all of the decimal digits, the English alphabet, and if zero and the letter O are represented by the same configuration, the possibility of a blank, though the last may also be secured by use of a relay to put out the light or lights, utilizing an additional signal available on a six channel input. Furthermore, if elegance of representation is discounted, the numeral 1 and the letter I may be represented by the same configuration giving the further possibility of a decimal point, and/or a dollar sign or the like. Theoretically, of course, the six channels could give rise to an 8 x 8 configuration of sixty-four possible relationships, but this is difficult to accomplish without deterioration of the accuracy and definite individuality of the displays.

Before proceeding to the discussion of a mechanical ar-

rangement for accomplishing the result in Figure 5, reference may be made to Figure 6 which indicates an array similar to Figure 5 but involving the use of other than straight line movements of the plates. Such straight line movements are attainable by sliding guidance, but that necessarily involves friction and linkages may be used instead. In the use of simple linkages curvilinear displacements are generally involved, but when the displacements are small, the deviations from straight line movement are also small. The array 76 in Figure 6 illustrates somewhat exaggeratedly how the positions will appear when straight line movements are not involved. It is still possible to approximate 60° intersections of the incremental paths, and the intersections in Figure 6 illustrate successive positions which may be taken by an opening 74 in its movements relative to the other plate. The other three holes indicated illustrate the closest permissible arrangement of the holes to prevent overlap of displays except as permitted as described above when special account is taken of certain of the display configurations.

Figure 7 illustrates a linkage arrangement together with an electromagnetic arrangement for securing the thirty-six relative positions with close approximation to the situation represented in Figure 5, with slight curvature as exaggeratedly illustrated in Figure 6.

One of the plates is here indicated at 78, the other being indicated at 79. Two fixed pivot points 80 and 82 mount equal arms 84 and 86 joined by a link 88 having a length corresponding to the spacing of the pivot points to give rise to a parallelogram linkage. To link 84 there is joined, conveniently at 92, a link 90 which is pivoted to the center of a transverse link 96 pivoted to members 98 and 100 which may be slightly flexible so as to effectively constitute extensions of solenoid plungers operable by windings 102 and 104. When the solenoids 102 and 104 are deenergized their respective plungers are withdrawn by springs (not shown) to secure definite positions of the ends of the link 96 against stops 106 and 108. When the solenoids are energized their plungers move into engagement with stops 110 and 112. It may be assumed that the connection at 94 is at the center of link 96 and that the movements of its ends between limit positions are the same. A pair of links 114 and 116 are connected to the ends of arms 84 and 86 and are equal in length with their ends joined by the link 118 corresponding in length to the link 88. The upper end of the link 118 is connected by link 20 to the plunger operated by a solenoid 122, the plunger movements being limited by stops provided at 124, withdrawal of the plunger being by a spring (not illustrated).

From the arrangement described it will be noted that if either of the solenoids 102 or 104 is alone energized there will be a single unit increment of movement imparted to the linkage point 94 and hence providing a unit incremental arc of movement of the end of lever 84. This unit increment of movement is illustrated by the vector 126. If both solenoids are simultaneously energized a double increment of movement is provided as indicated by vector 128. Thus there is imparted to link 118 movements in one direction of single or double incremental extent, corresponding to 1 and m of Figure 5. The plate 78 is secured to the link to partake of these movements. The movement imparted by the solenoid 122 which effectively acts about the pivot point 92 is represented by the vector 130 and theoretically should be three incremental units in length, corresponding to n of Figure 5. This movement is also imparted to the plate 78. Considering the increments to be quite small, as they would be in practice, they are closely straight line increments, and as indicated in Figure 7 are angularly spaced 60 degrees.

An identical arrangement is associated with the plate 80 and need not be described. The arrangement is such, however, that the two directions of movement imparted

to this plate correspond to the two directions of movement of the other, the lines joining the pivot points 80 and 82 and the corresponding pivot points at the right being at an angle of 60° with respect to each other. The result, therefore, is the attainment of relative movement as diagrammed in Figure 5, or, more precisely, as diagrammed in Figure 6 involving slight curvature of the movements. The six solenoids involved receive binary signals on six input channels, and with the arrangement disclosed give rise to the thirty-six relative positions of the plates. It will be obvious that if the incremental movements applied are greater, advantage may be taken of the full sixty-four possible relative positions controlled by six input channels. This would be accomplished, for example, by having the movement of solenoid 102 twice that of solenoid 104, and by having the plunger of solenoid 122 moving four unit lengths instead of three. However, utilization of such a system necessarily requires a still larger minimum permissible spacing between openings, representing less efficient use of the display area. For practical purposes, it is, therefore, sufficient to provide for thirty-six possible relative positions to provide a very complete numerical and arithmetical system.

The foregoing assumes that all the display units in a single display assembly are the same. However, by exerting some censorship on the complete freedom of message display, there may be provided display units having different sets of possible characters to be interchangeably plugged in in accordance with messages desired to be conveyed. For example, one of such display units might well contain the numerical digits and, for example, two-thirds of the alphabet including the most frequently occurring letters. It might then contain in addition only certain of the less frequent letters but be provided also with punctuation marks or the like. Another display unit might contain the same basic matters of numerals and most frequently used letters but a different content of the more infrequently used letters. With a limited number of such display units, analysis of an advertising message may reveal that by the choice of particular units a message could be fully conveyed but perhaps necessitating a slight shift of an array of words to make sure that a pair of infrequently used letters not on a single display device would not occur in the same position.

It will now be clear that the control devices may be quite simple in view of the utilization of a binary type of input involving a minimum number of channels. It is, of course, not necessary that in the case of numerical representation in decimal form that the decimal number should have the same magnitude as represented by the binary combination involved in its control. In most computing apparatus this would, of course, be desirable for simplicity, but if alphabetical displays are involved that situation need not be taken into account. The signals delivered through the control channels may be derived photoelectrically from perforated tapes, through feelers of such tapes, from magnetic records, or the like.

In view of the fact that the actuating members for the plates may have the form of relays in structure, it becomes possible not only to set the display device by means of short duration pulses but also to provide for electrical readout. An arrangement for doing this is illustrated in Figure 8 wherein the windings 134 and 136 may be typical of the electromagnet windings such as 24, 26, etc. shown in Figures 2 and 3. The lower terminals of these windings are connected to ground through a relay contact 138 which may be opened momentarily for reset purposes by energization of the relay winding 140. The windings 134, 136, etc. have similar connections and con-

sequently only those associated with winding 134 need be described. The armature indicated at 142 which has mechanical functions as heretofore described may be arranged to engage a contact 144 connected to a terminal 5 supply source 146 to provide a holding relay action. The movable switch element 142 may, of course, be insulated from the mechanical parts and be provided as a separate spring leaf on an armature such as 14. Connection is made between 142 and a terminal 148 to which setting 10 pulses may be delivered in any suitable fashion. A connection 150 extends to any suitable readout apparatus.

In operation for providing a new indication there may be first emitted a reset pulse to the winding 140 to open the contact at 138, thereby deenergizing all of the windings 134, 136, etc. Following reclosing of contact 138 15 selective pulses may be delivered at 148 to energize the windings selectively, these being held energized by the holding relay action. A display is thus provided which is permanent until resetting again occurs. In this arrangement the pulses introduced at 148 may be of short duration. Since under the holding action the relay arms 20 142 are selectively energized readouts may be taken as indicated at 150.

It will be evident that various changes in details of 25 construction and mode of operation may be made without departing from the invention as defined in the following claims.

What is claimed is:

1. A display device comprising a pair of plate members 30 guided for relative face-to-face sliding movements, their faces being closely adjacent to each other, at least two means for effecting relative step movements between said plates in approximately the same direction, one of said means imparting movement of an extent substantially 35 different from that imparted by the other, at least two additional means for effecting relative step movements between said plates in approximately another direction transverse to the first mentioned direction, one of the last mentioned additional means imparting movement of an extent 40 substantially different from that imparted by the other of said last mentioned additional means, thereby to effect by said step movements and absence of such movements a two dimensional array of relative positions of said plates, said plates being provided with light-transmitting areas, 45 arranged to be brought into coincidence selectively in the different relative positions of said plates, and means directing light through said coinciding light transmitting areas.

2. A display device according to claim 1 in which both 50 of said plates are movable.

3. A display device according to claim 1 in which said directions are substantially at right angles with respect to each other.

4. A display device according to claim 1 in which said 55 directions are substantially at 60° with respect to each other.

5. A display device according to claim 1 in which said means for effecting relative movement are electromagnetic.

6. A display device according to claim 1 in which the 60 means for effecting relative movements are electromagnets, said directions produce at least three different step movements.
